(57) **CLAIM**

The ornamental design for a portable storage device for cinema playback system, as shown and described.

DESCRIPTION

FIG. 1 is a right side perspective view of a portable storage device for cinema playback system, showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

The broken lines shown in the drawings depict portions of the portable storage device for cinema playback system that form no part of the claimed design.
